UNITED STATES PATENT OFFICE.

LEO C. BENITZ, OF PHILADELPHIA, PENNSYLVANIA.

LEAD-PENCIL.

SPECIFICATION forming part of Letters Patent No. 705,900, dated July 29, 1902.

Application filed December 27, 1901. Serial No. 87,430. (No model.)

To all whom it may concern:

Be it known that I, LEO C. BENITZ, a citizen of the United States, and a resident of Philadelphia, in the county of Philadelphia and 5 State of Pennsylvania, have made certain new and useful Improvements in Lead-Pencils, of which the following is a specification.

My invention is an improvement in the class of pencils whose leads are adapted to slide 10 freely and are secured in any position to which they may be adjusted by means of an elastic device which is arranged to work in frictional contact with the lead. I have devised an improvement whereby the lead is 15 held very firmly against movement in an upward direction, but may be readily drawn out when required, and is also prevented from rotation on its axis, as hereinafter set forth.

In the accompanying drawings, Figure 1 is 20 a face view of the inner sides of the longitudinal halves of a wooden pencil-body, which are formed with grooves and enlargements thereof according to my invention, a lead with an elastic band or ring being shown arranged 25 in the groove of one of said halves. Fig. 2 is a perspective view of a section of the lead with the elastic band applied. Fig. 3 is an enlarged cross-section on the line 3-3 of Fig. 1. Fig. 4 is an enlarged longitudinal section of 30 a portion of one of the halves of the pencil-body. Fig. 5 is an enlarged longitudinal section of a portion of a pencil constructed according to my invention. Fig. 6 is a longitudinal section of a pencil embodying a modification.

In Fig. 1 the numerals 1 and 1^a indicate the two like longitudinal halves of the wooden body of the pencil. Each of them is provided with an internal lengthwise half-round groove 40 2 to form when the parts 1 1^a are put together a cylindrical socket or opening for an ordinary cylindrical lead 3. The latter is adapted to fit in the socket so closely as to prevent it from wobbling or moving laterally therein 45 when the pencil is in use. At the distance of, say, an inch from the point of the pencil-body each of the halves 1 and 1^a is provided internally with a cavity, forming when the halves are put together, as in Fig. 5, a socket 4, adapted 50 to receive an elastic detainer 5 for the lead 3. The said socket 4 is practically a lateral enlargement of the groove 2, the same having

a square bottom and being tapered in an upward direction, as shown. The detainer 5 is a rubber band or ring, which encircles the 55 lead 3 and clasps it firmly. In any case the band 5 is made of such thickness that it cannot be forced up or down beyond the limits of the tapered socket 4. It is thus practically an elastic holder for the lead. 60

It will be seen that when the lead 3, with detainer 5 applied, is placed in the pencil-body 1 1^a, as shown in Figs. 1 and 5, the lead cannot be forced upward, since the greater the pressure on its point the more will the 65 detainer 5 be compressed in the tapered upper portion of the socket 4, and hence the more firmly will it clasp the lead, and yet when traction is applied to the lead 3 it may be drawn out of the body 1 1^a, as required, since the 70 lower edge of the band or ring 5 will then rest upon the square base or shoulder of the socket 4, and thus be caused to slide easily upward on the lead. In brief, by the construction and combination of parts shown the lead 3 is 75 held firmly and yet may be drawn out easily, while rotation on its axis is impossible. Further, there is no projection or protuberance on the body of the pencil, as required when a slide of the usual kind is employed. 80

In Fig. 6 a modified adaptation of the same principle is illustrated, but one of the longitudinal halves of a pencil-body being provided with a tapered socket and the detainer 5^a being a strip or small block of rubber in 85 place of a band or ring.

Having thus described my invention, what I claim as new, and desire to secure by Letters Patent, is—

1. A pencil-body having a lengthwise opening provided near the point with an enlargement forming a socket which is tapered upward, and a rubber band fitted in said socket, as shown and described. 90

2. A pencil-body having a lengthwise opening which is enlarged near the point and formed with a flat base and upward taper, and a lead, and encircling elastic band arranged in the enlargement of the opening, substantially as shown and described. 95

3. A pencil comprising a body having a lengthwise opening which is enlarged at one point and tapered upward, and an elastic piece held in the enlargement of the opening and 100

adapted to bear upon a slidable lead, as shown and described.

4. A pencil comprising a body having a lengthwise opening which is enlarged near the point, to form a cavity having a flat base and tapered upward from such base, and a lead and elastic piece fitted in such cavity and pressing upon the lead, substantially as shown and described.

10 5. A pencil-body having a lengthwise open-

ing which is enlarged near the point, to form a cavity having a flat base and tapered upward from such base, and adapted for reception of an elastic lead-detainer, as shown and described.

LEO C. BENITZ.
